UNITED STATES PATENT OFFICE.

LEWIS R. BORLAND, OF FRAZEE, MINNESOTA.

COLLAPSIBLE HOUSEHOLD SCREEN.

1,278,579.

Specification of Letters Patent. Patented Sept. 10, 1918.

Application filed May 22, 1917, Serial No. 170,303. Renewed July 26, 1918. Serial No. 246,925.

To all whom it may concern:

Be it known that I, LEWIS R. BORLAND, a citizen of the United States, residing at Frazee, in the county of Becker and State of Minnesota, have invented new and useful Improvements in Collapsible Household Screens, of which the following is a specification.

This invention comprehends the provision of a household screen which may be utilized for various purposes, and embodies a plurality of collapsible frame sections which when brought together in a collapsed condition produces a comparatively small compact article, with the screen fabric interposed between the component parts of the frame to be protected by the latter.

The nature and advantages of the invention will be better understood when the following detail description is read in connection with the accompanying drawings, the invention residing in the construction, combination and arrangement of parts as claimed.

In the drawings forming part of this specification like numerals of reference indicate similar parts in the several views and wherein:

Figure 1 is a rear elevation of the screen extended.

Fig. 2 is a view showing the same folded prior to collapsing the frame.

Fig. 3 is a sectional view taken on line 3-3 of Fig. 1.

Fig. 4 is a view of the screen completely folded.

Fig. 5 is an enlarged detail sectional view of the sliding connection between one of the bars and uprights.

Fig. 6 is a diagrammatic view of a screen of four uprights.

Fig. 7 is a similar view of a screen of five uprights.

A screen embodies in accordance with my invention a frame indicated generally at A, and suitable screen fabric indicated at B and attached to the frame in any suitable manner. The frame consists of a plurality of parallel uprights 10 which may be constructed of any suitable material, of cross sectional configuration and size without departing from the spirit of the invention. As shown in Fig. 1 three of these uprights are used in the production of a screen, and consequently attributes to the screen a substantially V-shaped form, but upon refer-

ence to Figs. 5 and 7 it will be noted that any number of uprights 10 may be employed in the production of the screen to vary the formation of the latter when in set up position for use. Irrespective of the number of uprights employed in a single screen, every two adjacent uprights are connected by diagonally disposed bars 11 which are pivotally connected together at their point of intersection as at 12, the opposite extremities of the respective bars being forked or bifurcated, while the prongs 12' of said extremities are pivotally associated with the lugs 13 projecting from diametrically opposite points of the collars 14. The collars 14 with which the upper extremities of the bars 11 are associated, are mounted for sliding adjustments on the uprights as well as rotation thereon, to permit the frame to be folded or collapsed in the manner shown. The uprights 10 adjacent their lower extremities are provided with reduced portions 15 about which the sleeves 14 connected with the lower extremities of the bars 11 are arranged. These latter mentioned sleeves while permitted rotation with respect to the uprights, are prevented from sliding adjustment upon the uprights as in the case with the other sleeves adjacent the upper ends of the latter. When the uprights are spaced, and the screen in a set up position for use, the structure is given a desired rigidity, through the instrumentality of the braces 17, which are interposed between the bars 11 and connected thereto as clearly shown in Fig. 1, but each of which braces are hinged at the center to permit the frame to be folded or collapsed in the manner to be presently described.

In practice, the screen can be given different formations when its use is desired, by arranging the uprights 10 in different positions with respect to each other, as will be readily understood. However, when it is desired to fold or collapse the screen the end uprights are swung in a direction about the center upright as a pivot, to a position whereby the screen fabric will be arranged on the inside of the uprights. This is the folded position of the screen prior to collapsing the frame, and is clearly illustrated in Fig. 2. When more than three uprights are used in connection with a single screen, the proper upright is selected for the pivot, and the remaining uprights swung in the direction so that the screen fabric will be disposed on the inside of the uprights. Refer-

ring now to Fig. 4 of the drawings, it will be noted that subsequent to the positioning of the uprights in the manner above stated, the braces 17 are broken at their center, to 5 permit the frame to be collapsed. The end uprights being disposed in juxtaposition as shown in Fig. 2, it is only necessary to move the remaining upright or uprights in the direction of the end uprights, to provide a 10 comparatively small compact article, during which operation the screen fabric B is gathered or positioned between the respective uprights of the frame and thus protected from injury during transportation from one place 15 to the other. As the uprights are brought together during the collapsing of the frame A, the collars 14 which are slidably mounted, move in the direction of the upper extremities of the uprights, while all of the collars 20 being rotatably mounted on the uprights permit the latter to be swung into any desired position about one of the uprights as a pivot, either to vary the form of the screen when in use or to facilitate the folding or 25 collapsing of the screen when its use is not desired.

While I have shown and described what I consider the preferred embodiment of the invention, I desire to have it understood that 30 I do not limit myself to this precise construction and arrangement, and that such changes may be resorted to when desired as fall within the scope of what is claimed.

What is claimed is:—

35 1. A collapsible household screen comprising a frame and a screen fabric secured thereto, said frame including a plurality of sections, each having spaced parallel uprights, diagonally disposed cross bars connecting each pair of uprights and pivoted at 40 their points of intersection, the upper ex-

tremities of said cross bars embracing said uprights, collars carried by said extremities and surrounding said uprights to permit relative rotation of the respective sections of the frame, and said sections to be swung in either direction to a position for use, said collars being also slidably associated with said uprights to permit collapsing of said frame, and means for holding the uprights rigidly 50 spaced in active positions.

2. A collapsible household screen comprising a frame and a screen fabric secured thereto, said frame including a plurality of sections each having spaced parallel uprights, diagonally disposed cross bars connecting each pair of uprights and pivoted at their point of intersection, said bars being connected with said uprights to permit the respective sections to be rotated in either 55 direction to assume different positions relatively, and to further permit said uprights to be closely associated in juxtaposition with the screen fabric positioned between the uprights, a brace rod interposed between said 60 diagonally disposed bars and connected thereto for holding the latter and said uprights rigid in active position, and said brace including hingedly connected sections.

3. A collapsible household screen comprising a frame including a plurality of parallel uprights, a pair of spaced collars rotatably mounted on each upright, the uppermost collars being also slidably mounted, diagonally disposed cross bars connecting 75 each pair of uprights and pivoted at their point of intersection, the said bars having bifurcated extremities pivotally connected with said collars, and means for holding said uprights rigidly spaced in set-up position. 80

In testimony whereof I affix my signature.
LEWIS R. BORLAND.
